FORMING AND PRESSURE DIES FOR PIPE-BENDING MACHINES

August Hellwig, Chicago, Ill.; Frank P. Hellwig,
administrator of said August Hellwig, deceased

Filed Feb. 5, 1958, Ser. No. 713,330

2 Claims. (Cl. 153—32)

This invention relates to improvements in pipe-bending machines. More specifically, it relates to improvements in the forming dies and wiping members or follow bars of such machines.

Existing dies result in two disadvantages. One is the flattening of the bent pipe into elliptical section, a form heretofore referred to as final. Another is the indentation of the pipe, in which the outline of the forming die is impressed into the pipe, particularly at the starting portion of the bend.

It is an object of this invention to provide improved forming dies and follow bars, adapted to form bends of true circular section and free of indentation.

It is another object to provide means whereby the bending force is applied initially at a pre-determined point with respect to the fulcrum of the bend, and thereafter applied at varying points determined independently of the judgement or skill of the operator.

Still another object is to provide dies with novel grooves, dimensioned in accordance with a newly discovered principle herein described.

Other objects and advantages of the invention are explained with reference to the accompanying drawings, of which:

Figure 1 is a fragmentary plan view of a commercial pipe-bending machine.

Figure 2 is a plan view on a larger scale, of the improved forming die and follow bar, shown in their relative starting positions.

Figure 3 is a sectional view, taken on the line 3—3 of Figure 2.

Figure 4 is a plan view similar to Figure 2, showing the improved forming die and follow bar after advancing operatively.

Figure 5 is a sectional view, taken on the line 5—5 of Figure 4.

Figure 6 is a diagrammatic view, illustrating the dimensioning of the novel grooves.

It should be understood at the outset, that the present invention is concerned solely with the co-operation of the forming dies and follow bars, and that other elements are shown and described only as they are incidental. With this in mind, Figure 1 illustrates a commercial pipe-bending machine such as is used to bend thin-wall electrical conduit. It comprises in part, the body 10 of a hydraulic ram, to which links 11 are attached by studs 12. A pin 13 rotatably supports a roller 14. Bearing against this roller is a follow bar 20' provided with a longitudinally extending groove 21', dimensioned to accommodate a pipe P.

A plunger 15 is pivotally attached by a pin 16 to a forming die 30', which is provided with an arcuate groove 31'. The pipe P is tangentially held in this groove by the U-shaped strap or saddle 17, which is pivotally attached by a pin 18 to the forming die 30'.

When the plunger 15 is caused to advance, it rotates

2

the forming die 30', which carries the pipe around with it, and forms a bend nesting in the arcuate groove 31'. This process is well known to those skilled in the art of bending pipe.

5 Existing forming dies and mating follow bars are commonly made with a combined depth of grooves which measures less than the diameter of the pipe, as indicated at 19. This aggravates the inherent tendency of the pipe to flatten. Also, it was heretofore believed essential to 10 restrict minutely, the portion of the pipe being worked, so that drawing of the metal occurred rather than bending. A characteristic result is the indentation of the pipe, particularly at the starting portion of the bend, in which the outline of the forming die is noticeably impressed 15 in the pipe.

The co-action of several improvements serves to overcome these disadvantages. Looking now at Figures 2 and 3, the improved follow bar 20 has a groove 21 bordered by flat portions 22. These serve as rails, on 20 which the die 30 rolls. Starting at the end 23, the rails slope at a small angle to an intermediate point 24. The groove 21 is deepest at the end 23, and decreases gradually in depth to the point 24. For the remaining length of the follow bar 20, the groove 21 is of uniform depth. 25 At the start of a bending operation, the peripheral edges 32 of the forming die bear against the rails 22 near the deeper portion of the groove 21. The excess depth affords a space as indicated at 25. Obviously there is no force tending to crush the pipe.

30 As shown in Fig. 2, the normal 3—3 passes through the point 26, a few degrees from the start of groove 31. The pipe P is shown at a small angle to the groove 21. This situation occurs when sufficient force is exerted to flex the pipe longitudinally to its yield point, but without 35 causing permanent bending.

The pipe's impingement in groove 31 terminates at point 26. This point is referred to as the momentary fulcrum, against which the pipe is bent. Further bending results in advancing the terminus of the bend, with a 40 corresponding advance of the momentary fulcrum.

Heretofore, the pipe was closely confined by the combined grooves of the forming and pressure dies, and force was exerted by the pressure die at a point substantially coincident with the momentary fulcrum, without first 45 flexing a substantial portion of the pipe. The result is more of a drawing of the metal than one of bending.

In the present invention, as shown in Fig. 2, the pipe is flexed in a long curve, extending from the starting end of the pressure die to a point 28. A normal through 50 this point intersects the opposite side of the pipe at 27, and defines an angle of 15° with the normal 3—3. It is apparent that in this situation bending force is applied at a point 28 which is 15° removed from the momentary fulcrum 26. As a result, the pipe is flexed into a long curve, longitudinally equivalent to a 15° arc.

As the forming die rolls further along the pressure die, the angle between the momentary fulcrum and the point at which force is applied, gradually decreases. When 55 the forming die has rotated 15°, it assumes the position shown in Fig. 4. The normal 5—5, drawn through the momentary fulcrum, simultaneously passes through the point 28 in the forming die, defining the point at which bending force is exerted. Thereafter, until the completion of the bend, this relationship remains constant.

60 The present invention limits the flexing of the pipe to an initial portion of the bending cycle, during which the flexed portion of the pipe decreases in length until the momentary fulcrum is substantially in line with the point at which force is exerted by the pressure die. If 65 the flexing is permitted to extend throughout the bending cycle, or to a portion substantially exceeding at 15° arc, the result is a wrinkling of the pipe. Limiting the flexing

as described is significant, because while some older bending devices are provided with means for adjusting the initial position of the follow bar with respect to the fulcrum, the present invention is the first to provide for the pre-determined and automatic variation of this relationship.

As an example, for bending thin-wall conduit of $1\frac{1}{4}$ " trade size, the added depth of the groove at the end 23 is $\frac{1}{16}$ ". The length of the inclined portion of the rails, from the end 23 to the point 24 is 3". For pipes of other diameter, material or wall-thickness, the length and rise of the inclined portion of the rails 22 may be determined experimentally.

Older forming dies and follow bars were made with grooves which, besides being less in depth than the diameter of the pipe, were also greater in width. This was done to accommodate the pipe after it had been permitted to flatten.

Other dies have been dimensioned to form bends which are permanently and substantially flattened in the plane of the bend. While such bends may be adaptable to particular applications, they do not conform to the true roundness which has been the long-sought object of most pipe-bending inventions.

It is well known that a pipe or tube may easily be compressed or flattened. Beyond this bare fact, no data has ever been compiled of the extent to which various sizes of pipes may be laterally compressed without permanent distortion. Neither has lateral compressibility been previously recognized as the determining factor in dimensioning the grooves of forming dies to an optimum value.

I have discovered that there is, for every right section of pipe, a lateral elastic limit which bears a direct relationship to the bending of the pipe, and to the correct dimensioning of the grooves in the forming dies. Moreover, I have discovered a simple method for determining this lateral elastic limit.

If a short piece of pipe is clamped between the jaws of a machinist's vise, it may be measured while being subjected to increasingly greater compression. It is a simple matter to determine in this manner, the ultimate compression from which the pipe still resumes its full diameter upon release. Both the minor and major axis are recorded at the ultimate compression.

The minor axis determines the correct width of the groove in the forming die. The major axis determines the correct depth of the combined grooves in the forming die and follow bar. A few thousandths of an inch may be added to both the width and depth, as a safety factor. This dimensioning, as well as a further novelty in the grooves, is illustrated in Figure 6.

The groove 31 is formed with a true semi-circle as the base, with tangent portions T extending therefrom. The diameter of the semi-circle is equal to the minor axis described above. The tangent portions T are so dimensioned that the total depth of the groove 31 is six-tenths of the major axis. Heretofore it has always been customary to make the grooves in the forming die and follow bar of equal depth. The purpose of the additional depth of groove in the novel forming die is to insure that the pipe is confined laterally before it bottoms in the groove, so that it cannot flatten when flexed at the beginning of the bending operation.

The groove 21 is formed as the arc of a circle having the same radius as the groove 31, and having a depth of four-tenths of the major axis. This is substantially equal to an arc of 144 degrees.

The combined grooves 21 and 31 encircle the pipe at whatever point the follow bar 20 bears against the forming die 30. It will be understood that the groove 21 is deepened in the inclined portion of the follow bar as previously explained.

Bends formed by the co-operation of the improved forming die and follow bar are of true circular section. If at any portion of a bend, measurements are taken of

the diameter in the plane of the bend and lateral thereto, the difference between such measurements will not exceed the accidental variations similarly measured at unbent portions of the pipe.

5 The invention has been described with reference to an illustrative pipe-bending machine, and with particular means for varying the position of the pressure die with respect to the fulcrum of the bend. Obviously the advantages extend to other pipe-bending machines, and to alternative means for varying the relative position of the pressure die.

It is therefore not the intention to limit the invention to the particular embodiment herein described. Rather, the intention is to include all such variations and alternative embodiments and adaptations as fall within the spirit of the invention, and of the appended claims.

I claim:

1. A pipe-bending machine comprising, in combination, a pressure die having an initial pressure application end, 20 a final pressure end, and sidewalls therebetween defining a groove adapted to partially receive a pipe to be bent, said pressure die groove being of true semi-circular configuration bordered by flat surface portions adapted to serve as rails running the length of said groove, a forming die having a curved surface provided with sidewalls at the periphery thereof defining a groove adapted to cooperate with said pressure die by circumferentially enclosing said pipe while said curved surface bears upon the rails of said pressure die, said forming die groove being of true 25 semicircular configuration terminating in tangential flats at the inner portions of the sidewalls, means pivotally attached to said forming die tangentially holding said pipe in the forming die groove, and means for rotating said forming die whereby said pipe is carried around to form a 30 bend nesting in the curved groove of said forming die, each of said grooves having a width equal to about the minor compressive axis of said pipe, the depth of said forming die groove plus tangential flats being equal to about 0.6 of the major compressive axis of said pipe and 35 the depth of said pressure die groove being equal to about 0.4 of the major compressive axis, said rails sloping at a small angle from said initial pressure end to a point intermediate said initial pressure end and said final pressure end to provide therebetween a groove of depth slightly 40 greater than about 0.4 of the major compressive axis, whereby the initial bending force can be applied to a pipe at a point along its length substantially removed from the point of first impingement on the forming die so that a greater portion of the pipe can be worked initially, while 45 the point at which the pressure die exerts force is being automatically varied to gradually change the bending force to a drawing force.

2. A pipe-bending machine comprising, in combination, a pressure die having an initial pressure application end, 50 a final pressure end, and sidewalls therebetween defining a groove adapted to partially receive a pipe to be bent, said pressure die groove being bordered by flat surface portions adapted to serve as rails running the length of said groove, a forming die having a curved surface provided with sidewalls at the periphery thereof defining a groove adapted to cooperate with said pressure die by circumferentially enclosing said pipe while said curved surface bears upon the rails of said pressure die, said forming die groove terminating in tangential flats at the 55 inner portions of the sidewalls, and means for rotating said forming die whereby said pipe is carried around to form a bend nesting in the curved groove of said forming die, each of said grooves having a width equal to about the minor compressive axis of said pipe, the depth of said forming die groove plus tangential flats being equal to about 0.6 of the major compressive axis of said pipe and the depth of said pressure die groove being equal to about 0.4 of the major compressive axis, said rails sloping at a small angle from said initial pressure end to a 60 point intermediate said initial pressure end and said final pressure end to provide therebetween a groove of depth slightly greater than about 0.4 of the major compressive axis, whereby the initial bending force can be applied to a pipe at a point along its length substantially removed from the point of first impingement on the forming die so that a greater portion of the pipe can be worked initially, while the point at which the pressure die exerts force is being automatically varied to gradually change the bending force to a drawing force.

75

pressure end to provide therebetween a groove of depth slightly greater than about 0.4 of the major compressive axis, whereby the initial bending force can be applied to a pipe at a point along its length substantially removed from the point of first impingement on the forming die so that a greater portion of the pipe can be worked initially, while the point at which the pressure die exerts force is being automatically varied to gradually change the bending force to a drawing force.
